US0D1113957S

(12) **United States Design Patent** (10) **Patent No.:** **US D1,113,957 S**
(45) **Date of Patent:** **** Feb. 17, 2026**

(54) **DISPLAY SCREEN OR PORTION THEREOF WITH GRAPHICAL USER INTERFACE**

(71) Applicant: **Apple Inc.**, Cupertino, CA (US)

(72) Inventors: **Graham R. Clarke**, Scotts Valley, CA (US); **Andrew Patrick Clymer**, San Jose, CA (US); **Alan C. Dye**, San Francisco, CA (US); **Thalia Jimena Echevarria Fiol**, Cupertino, CA (US); **Christopher P. (57) **CLAIM**

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is another embodiment thereof.

The broken lines in the figures show a display screen or portion thereof, and form no part of the claimed design.
